CORE COVERING MACHINE

Henry Z. Cobb, Providence, R. I., assignor to
 United States Rubber Products, Inc., New York,
 N. Y., a corporation of Delaware

Application June 28, 1935, Serial No. 28,802

7 Claims. (Cl. 117—34)

This invention relates to machines for applying oppositely wound coverings upon cores and more particularly to machines for applying these coverings to elastic cores.

5 It has been proposed heretofore to apply oppositely wound coverings upon an elastic core but in the prior machines one covering is applied to the elastic core at a considerable distance from the point at which the other covering is applied,

10 and since the core being covered is, in most cases, quite small in size and stretches readily, it may tend to stretch and contract or "breathe" between the winding points during the winding operation, thus causing irregularities to occur

15 in the covering of the core. Furthermore, any rotation of the core about its own axis between the winding points will tend to change the number of wraps in the inner cover.

The present invention seeks to overcome these 20 objectionable features of the core-covering machines proposed heretofore and contemplates a construction whereby the two oppositely wound coverings are applied to the core at nearly the same point to thereby provide more uniform 25 covers upon the core.

In carrying out the present invention, one important feature resides in the arrangement whereby one of a pair of winding units employed to wind a covering yarn about the core, is arranged in reversed relation to the other unit so as to bring its winding point adjacent the winding point of the other unit to cause the opposite windings to be applied to the core at nearly the same point.

35 Another feature of the invention resides in the construction whereby one of the pair of winding units just referred to is supported for movement into and out of alignment with the other unit to thereby facilitate transfer of the yarn supply 40 packages to and from the core-covering spindles.

A more specific feature of the invention resides in the construction whereby one of the pair of winding units is tiltingly mounted for movement into and out of alignment with the other unit, 45 and in locking means whereby the tiltingly mounted unit may be easily and quickly locked in its operative position and released therefrom.

50 Other features of the invention and novel combination of parts in addition to the above will be hereinafter described in connection with the accompanying drawings illustrating one good, practical form thereof:

In the drawings:

55 Fig. 1 is a transverse sectional view through a core-covering machine showing the core-cover-

ing units arranged in accordance with the present invention;

Fig. 2 is a front elevation of part of the machine of Fig. 1;

Fig. 3 is a view similar to Fig. 1 illustrating 5 the core-feeding means, and the lower covering unit is shown in its tilted position;

Fig. 4 is a top plan view of the lower winding unit; and

Fig. 5 is a plan view of a swinging guide arm 10 provided between the two winding units.

The various parts of the machine shown may be supported by the transverse end and intermediate frames 10 that are connected by the longitudinally extending beams 11, 12 and connecting bars 13. The number of the frames 10 employed may vary with the length of the machine and these frames may be provided with legs for supporting the mechanism the desired distance from the floor.

20 While the machine of the present invention may be employed to cover different types of flexible cores, it is designed primarily to form a right and left hand spiral covering upon an elastic or rubber core in the manufacture of elastic yarn. 25 The winding means shown comprises an inverted upper unit 14 and an upright lower unit 15; that is, one unit is arranged in reverse relation to the other. These units during their winding operation are supported in axial alignment with each 30 other so that the core to be covered can be advanced through the aligned hollow spindles with which the units 14 and 15 are provided.

35 The upper winding unit 14 in the construction shown comprises an electric motor the outer casing 16 of which is mounted in a supporting frame 17 bolted to a bracket 18 which, in turn, is rigidly secured to the upper longitudinally extending beam 11. The rotor of the electric motor 16 is secured to the hollow core-receiving 40 spindle 19 which spindle, it should be noted, projects downwardly from the motor to receive the yarn supply package 20 below the operating motor. The yarn supply 20 may be wound on a spool adapted to fit over the spindle 19, and in 45 order to increase the frictional engagement between the spindle and the spool to retain the latter in place thereupon, the spindle may be provided with recesses at its opposite sides in which the bowed springs 21 are provided. The 50 spool 20 may also be provided with a notch, not shown, adapted to receive the driving key 22 upon the spindle 19.

The lower winding unit 15 may be provided with a similar electric motor 23 mounted in a 55

casing 24, which casing is bolted or otherwise secured to the supporting bracket 25 and the rotor of this motor is secured to and drives the hollow core-receiving spindle 26 which extends upwardly from the motor and is adapted to receive a yarn supply package or spool 27.

By thus supporting the lower winding unit 15 in an upright position and the upper winding unit in an inverted position these winding units will 10 operate to wind a right and left hand cover upon the core at nearly the same point. This arrangement, however, serves to bring the adjacent ends of the spindles 19 and 26 so close together that there is not room between them to permit the 15 application of the yarn supply spools to and their removal from the spindles.

One important feature of the present invention, therefore, resides in the construction and arrangement whereby one of the pair of winding 20 units may be readily moved to and from its core-winding position so that the adjacent ends of the spindles may be separated sufficiently to permit the ready placing of the spools upon and 25 their removal from the spindles. This desirable object is secured in the construction shown by pivotally mounting the bracket 25 which supports the lower unit 15 upon the longitudinally extending bar 13 so that this bracket may swing the desired amount in a vertical plane, as will 30 be apparent from Fig. 3. The lower end of the bracket 25 in the construction shown is bifurcated to straddle the bar 13 and may be secured upon this bar by the transversely extending pins 28 (see Fig. 1). Movement of the bracket 25 35 longitudinally of the bar 13 may be prevented by providing this bar with the collars 29 that are rigidly secured to the bar 13 at each side of the bifurcated bracket 25 as will be apparent from Fig. 2. The angle through which the bracket 25 40 is permitted to swing may be limited by the chain 30, one end of which is secured to this bracket and the other end is secured to the beam 12.

It is important that the means just described for swingingly mounting the lower unit 15 shall 45 serve to support the winding unit rigidly in accurate alignment with the upper winding unit 14 throughout the winding operation. To this end, in the construction shown, the bracket 25 is provided with a pin or plug 31, the outer end of 50 which may be tapered, and this pin is adapted to fit accurately in a correspondingly shaped hole 32 formed in the beam 12 to thereby accurately center the bracket 25 when it is swung upwardly into abutting engagement with the beam 12.

It is desirable to provide manually controlled 55 means for locking the bracket 25 in the core-covering position and this is accomplished in the construction shown by securing to the upper portion of the bracket the spring-operated latch 60 33 which is slidably mounted in the latch casing 34. This latch is so positioned that its lower end will engage a shoulder or abutment 35 attached to the beam 12. The latch 33 may be raised to release the bracket 25 for swinging movement 65 by depressing the outer end of the hand-operated lever 36 which is rigidly secured to the shaft 37 journaled at the upper end of the bracket 25 and a projection 38 secured to this shaft engages under a collar 39 secured to the stem of the latch 70 33 to raise the latch.

In the construction shown, the core 40 to be covered is supplied by a spool 41 and this spool may be provided with a supporting shaft 42 journaled in the spaced yokelike ends of the bracket 75 43 which bracket is rigidly secured to the lower

end of a vertically operating rod 44. As the core 40 unwinds from the spool 41 it passes upwardly through a guide eye 45 supported by an arm 46 that projects laterally from the bifurcated portion of the bracket 25. This guide eye serves to center the core 40 with respect to the bore of the lower spindle 26 and between the adjacent ends of the spindles 15 and 26, is preferably provided a swinging arm 47 which is provided with the guide eye 46. The arrangement is such that this arm 47 may be swung to and from a position of axial alignment with the spindles, as will be apparent from Fig. 5 wherein the bracket is shown in full lines in its core-guiding position and in dotted lines in the position in which it 15 has been swung laterally sufficiently to clear the yarn supply spool for the upper spindle when it is being transferred. The means shown for swingingly supporting the arm 47 comprises the shaft 49 journaled in a bracket 50 mounted upon 20 the upper end of an upright 50^x. The shaft 49 has rigidly secured to its upper end the plate 51 which is provided with a notched portion 52 that cooperates with a fixed pin 53 to thereby limit the angle through which the arm 47 may be 25 swung, and a spring 54 secured to the pin 53 and an upstanding ear 55 upon the plate 51 serves to hold the arm 47 in each of the positions in which it is shown in Fig. 5. The arm 47 is preferably secured to the shaft 49 for vertical adjustment thereupon by means of a thumb screw 56.

At the upper end of the upper winding unit 14 is preferably provided a fixed guide eye 56 supported by the bracket 57 in axial alignment with this winding unit and the core 40 passes in the construction shown from the guide eye 56 about a roller 58 the trunnions of which are journaled in the spaced yokes of the supporting bracket 59 secured to the operating rod 44. The core 40 40 passes from the roller 58 through a pigtail 60 secured to a traverse bar 61 and passes from this pigtail about the take-up reel 62 the supporting shaft 63 of which is journaled in the spaced yokes of the bracket 64 secured to the upper end of the 45 operating rod 44.

The operating rod 44 is supported for vertical sliding movement and the construction is such that when this rod is lowered the core supply spool 41 will engage the driving roller 65, the upper roller 58 will engage the second driving roller 66 and the reel 62 will engage the third driving roller 67 to thereby feed the core upwardly throughout the winding operation as more fully set forth and claimed in my Patent No. 1,976,328 55 granted October 9, 1934. When the rod 44 is raised, as shown in Fig. 3, the core-feeding operation will be suspended, as will be apparent from this figure. The means shown for raising and lowering the operating rod 44 comprises a hand-operated lever 68 which is pivotally supported at 69 and a bifurcated end of this lever embraces the rod 44 and lies between the spaced collars 70 secured to this rod. Spring means is provided for holding the operating lever 68 in the core-feeding position in which it is shown in Fig. 1 and in the non-feeding position in which it is shown in Fig. 3, and to this end the trunnioned portion of the lever 68 is provided with the V-shaped projection 71 which cooperated with a 65 spring-pressed plunger 72 that is supported by the beam 11.

In order to effect the desired winding operation, it is necessary to associate with each of the 70 yarn-supporting spindles some form of spinning 75

element to maintain a proper tension upon the yarn during the core-covering operation. In the construction shown each winding unit is provided with a ring and traveler. The ring 73 for the 5 upper spindle in the construction shown is secured to the underface of a metal plate 74 which is supported by the upright 50* extending upwardly from the lower beam 12. The ring 75 for the lower spindle in the construction shown, is 10 secured by screws 76 to a metal plate 77 that is fastened to the upper end of the swinging bracket 25.

During the winding operation the yarn supplied by the lower spool 27 passes from this spool 15 through an opening in the plate 77 to the traveler 78 and from this traveler to the lower end of a guide 48. The yarn supplied by the upper spool 20 passes downwardly through an opening in the plate 74 to the traveler 79 and from this traveler 20 to a guide eye 80 mounted at the lower end of the spindle 19.

When it is desired to stop the winding operation, it is important that means be provided for quickly stopping the rotation of the driving spindles. This is accomplished in the construction shown by providing the rotor of the upper motor with a friction shoe 81 adapted to be engaged by a braking collar 82 which is supported and operated by a lever 83 that is pivotally supported at 30 84 and this lever is provided with a spring 85 which continuously urges the lever in the brake-applying direction. The outer end of this lever lies in the path of a collar 86 secured to the operating rod 44. The arrangement is such that when this rod is lowered to the core-covering position the collar 86 will hold the lever 83 in the brake-releasing position and when this rod is raised the spring 85 will operate the lever 83, to apply the brake and stop the upper motor. The 35 rotor of the lower motor is provided with the friction shoe 87 which is adapted to be frictionally engaged by the braking-collar 88 which is under the control of the lever 89. This lever is pivotally supported from the motor frame at 90 40 and is urged in the brake-applying direction by the spring 91 and during the core-winding operation this lever is held in its brake-off position by a collar 92 positioned upon the rod 44 to hold the outer end of the lever 89 depressed. The movement of the rod 44 also preferably serves to control the current supplied to the motors 16 and 23 45 to operate them.

The core-feeding mechanism described serves to tension the core as it is drawn upwardly 50 through the winding spindles and the lower winding unit serves to helically wind the first covering upon the core in one direction while the upper unit serves to wind the second covering upon the core in the opposite direction, the arrangement being such that both covers are applied to the core at nearly the same point.

Having thus described my invention, what I claim and desire to protect by Letters Patent is:

1. In a machine for helically winding yarns in 55 opposite directions upon a core, in combination, a pair of winding units each including a hollow core-receiving spindle for supporting and rotating a supply of yarn, means for rotating said spindles in opposite directions about the core, one unit being arranged in axial alignment but in reverse relation to the other to bring its winding point adjacent the winding point of the other unit to thereby apply right and left hand windings to the core at nearly the same point, and 60 means for supporting one of said units for move-

ment relative to the other so that the spindles may be separated sufficiently to permit the placing of a supply of yarn on each spindle.

2. In a machine for helically winding yarns in opposite directions upon a core, in combination, a pair of winding units each including a hollow core-receiving spindle for supporting and rotating a supply of yarn, means for rotating said spindles in opposite directions about the core, one unit being arranged in axial alignment but in reverse relation to the other to bring its winding point adjacent the winding point of the other unit to thereby apply right and left windings to the core at nearly the same point, and means for supporting one of said units for tilting movement out of alignment with the other to thereby separate the ends of the spindles sufficiently to permit the placing of a supply of yarn on each spindle. 10

3. In a machine for helically winding yarns in opposite directions upon a core, in combination, a pair of winding units each including a hollow core-receiving spindle for supporting and rotating a supply of yarn, means for rotating said spindles in opposite directions about the core, one unit being arranged in axial alignment but in reverse relation to the other to bring its winding point adjacent the winding point of the other unit to thereby apply right and left windings to the core at nearly the same point, means for supporting one of said units for tilting movement out of alignment with the other to thereby separate the ends of the spindles sufficiently to permit the placing of a supply of yarn on each spindle, and latch means for locking the tilting unit 15 in its operative position. 30

4. In a core-covering machine, in combination, a pair of winding units, each including a hollow core-receiving spindle for supporting and rotating a supply of yarn, a ring and traveler for each spindle, means for rotating said spindles in opposite directions about the core, one unit being supported in axial alignment but in reverse relation to the other to bring its winding point adjacent the winding point of the other to thereby apply right and left windings to the core at nearly the same point, means for supporting one unit for movement relative to the other and the ring and traveler for this unit being mounted thereupon to move therewith. 45

5. In a core-covering machine, in combination, a pair of winding units, each including a hollow core-receiving spindle for supporting and rotating a supply of yarn, yarn-guiding means co-operating with each spindle to guide the yarn outwardly away from the yarn supply and to the winding point, driving mechanism for rotating the spindles in opposite directions about the core, one unit being supported in axial alignment but in reverse relation to the other to bring the winding points close together, and means for supporting one unit for movement relative to the other to separate said spindles and said yarn-guiding means for this unit being mounted thereupon to move therewith. 55

6. In a machine for helically winding yarns upon a filamentary core, in combination, a pair of winding units each including a hollow core-receiving spindle for supporting and rotating a package of yarn, means for independently rotating said spindles about the core, one unit being arranged in axial alignment but in reverse relation to the other to bring its winding point adjacent the winding point of the other unit to thereby apply an inner and outer helical wind- 70

ing upon the core at nearly the same point, and means for supporting one of said units for movement relative to the other so that the spindles may be separated sufficiently to permit the placing of a package of yarn on each spindle.

7. In a core-covering machine, in combination a pair of winding units each including a hollow core-receiving spindle for supporting and rotating a supply of yarn, means for independently rotating said spindles about the core, means for advancing the core upwardly through both spin-

dles, one unit being arranged in axial alignment but in reversed relation to the other to bring its winding point adjacent the winding point of the other to thereby apply an inner and outer cover upon the core at nearly the same point, and the spindle of the reversed unit having its downwardly extending end constructed and arranged to guide the covering yarn downwardly to the winding point and about the core as the latter passes upwardly through this spindle.

5

HENRY Z. COBB.
